ERNEST F. YOST AND WILLIAM H. SMITH, OF NEW YORK, N. Y.

THERMO-ELECTRIC CELL.

SPECIFICATION forming part of Letters Patent No. 660,138, dated October 23, 1900.

Application filed June 28, 1900. Serial No. 21,902. (No model.)

To all whom it may concern:

Be it known that we, ERNEST F. YOST and WILLIAM H. SMITH, of the borough of Brooklyn, city of New York, State of New York, 5 have invented a new and useful Improvement in Thermo-Electric Cells, of which the following is a specification.

Our invention relates to an improved form of thermo-electric cell; and it consists in the 10 construction of said cell whereby a current of refrigerating fluid is led through its interior, in the arrangement of the fluid-conducting tubes to serve also as circuit-terminals in the cell, in the shielding of one of the elements 15 of the thermo-electric couple by a substance which prevents said element being attacked by any constituent of the other element, in the construction of the joint to be heated so as to insure closeness under differences of 20 temperature and to compensate for contraction and expansion of the cell-body, in the specific combination of parts in the cell herein illustrated, and in the various other features of improvement, as more particularly pointed 25 out in the claims.

In the drawings, Figure 1 is a vertical section of our improved thermo-electric cell on the line 1 1 of Fig. 2. Fig. 2 is a vertical section on the line 2 2 of Fig. 1.

30 Similar letters of reference indicate like parts.

A is a body of metal, preferably copper, to which mass the heat which excites the cell is applied. To the face B of the mass A is 35 secured, as by brazing or soldering, a shell or casing C, preferably made of an alloy containing iron, copper, and nickel, commonly known in the market as "I A metal." The exact proportions are: iron, 0.80 per cent.; 40 nickel, 42.10 per cent., and copper, 57.10 per cent.; but it may be constructed of copper or any other metal which is electropositive in the thermo-electric couple of the cell. Upon the said face B is also brazed or soldered or otherwise 45 suitably secured the conducting-piece D, which is constructed and arranged for a special purpose, to be hereinafter noted. As specifically illustrated, it is made of a short copper tube bent over, with its parts substantially parallel, the part E being flattened, and thus made substantially solid, and the other part F left tubular. Surrounding the bend

in the piece D is a sleeve S, of asbestos or other insulating material. The exposed surface of the part E is also covered with insulating material T, such as any suitable insulating-paint. The piece D is embedded in a mass G of metal, which in the cell is electronegative. We preferably employ antimony, either alone or in alloy, with another metal, 60 such as zinc; but it is to be understood that in no case is the proportion of metal with which the antimony is alloyed to be so great as to permit any attack by said alloying metal upon the electropositive element with which 65 it may come in contact.

The shell C has a lining of refractory insulating material H, such as mica or asbestos, and is filled for a distance equal to about five-eighths of its height, measured from the face B 70 of the copper mass A, with an alloy of antimony and zinc I, which forms the main portion of the electronegative element. The proportion of zinc in the alloy need not be considered with reference to its attacking 75 effect upon the electropositive element, because the latter is shielded by the mass G, in which it is embedded, this being the object of said mass.

In the walls of the shell C are made opposite openings, one of which receives the short copper sleeve J, soldered or otherwise secured in place and lined with refractory insulating material K. This sleeve receives the copper tube L, which extends into the 85 shell and has its inner end flared and lined with insulating material M. In said end is received the tapered end of a copper tube N, which passes through the shell-wall and is soldered or otherwise secured therein. This 90 junction of the tubes L and N is watertight. A plate of copper O is placed upon the face of the mass I and the remainder of the interior of the shell is filled with solder P, in which the sleeve and tubes are firmly 95 embedded. A layer of insulating material R covers the solder, and finally the large end of the shell is closed by a plate Q, of copper, also soldered in place. The whole cell thus becomes a solid mass of various materials, 100 all firmly united together. When it is in operation, the heating-flame is applied to the projecting copper mass A, and thus the joint between the piece D, which is electroposi-

tive, and the electronegative masses G I becomes elevated in temperature. With this joint the tube N is in electrical connection through the shell C. On the other hand, the 5 tube L, which is insulated from the shell C, is in electrical connection with the electronegative mass I. The joint between tube L and mass I is cooled by passing a stream of water or other refrigerating fluid continuously through the tubes L and N while the element is in operation. A difference of electrical potential is therefore caused between the hot joint at D and the cool joint at the tube L. The tubes L and N therefore, in 10 addition to serving as conduits for the refrigerating fluid, also serve as terminals and circuit connections for the cell.

Referring again to the piece D, if the metal within the shell C were firmly held at both 20 ends of the shell expansion of the cell would result in a cracking or tearing open of the middle portion of the alloy I. The bend of the piece D and the part E of said piece are prevented from adhering to the surrounding 25 metal by the insulating-coverings. Therefore the parts F E may open slightly under strain, and thus prevent the difficulty above noted. The joint between the tubular part F of piece D and the inclosing mass G obviously becomes tighter when the part F expands.

The following principal advantages result from the above-described construction:

First. Refrigeration of the joint to be cooled 35 takes place in direct proximity to the electronegative metal and within the mass of the cell itself. This allows of the cell being made of probably the smallest possible size, since it is not necessary to enlarge its proportions. 40 in order to give an extensive radiating or cooling surface, as is requisite when the atmosphere or the proximity of a water-jacket at the base only of the cell is depended upon for cooling purposes.

Second. There is a continuous flow of water or other refrigerating liquid through the electronegative element, so that abstraction of heat at the joint to be cooled is continuously effected.

Third. The circulating-tubes serve both as 50 conduits for the water-supply and also as circuit-terminals for the cell or connections between successive cells.

Fourth. The large heat-receiving mass A 55 serves substantially as a heat-reservoir and insures uniform and steady heat-supply at the joint to be heated.

Fifth. The construction of the contact-piece D prevents any impairment of the heated 60 joint by reason of contraction or expansion of the body of the cell and secures the tightness of the joint.

Sixth. The embedding of the heated joint in a metal or alloy containing no substance 65 which will attack the electropositive metal, tending to render it brittle or otherwise impair it, allows of the use of an electronega-

tive alloy which otherwise, because of some one or more of its ingredients, might attack the electropositive metal, since the electropositive metal is shielded from such attack. 70

Seventh. The presence of the copper plate O between the mass I and the solder in which the water-tubes are embedded insures a close conducting-joint between the electronegative 75 mass I and the mass of solder P.

Eighth. The whole element is a firm solid mass having no projecting plates or other portions intended to increase the radiating-surface and no parts liable to be bent or 80 broken-off or otherwise injured.

Ninth. The water-tubes serve both as conduits for a refrigerating fluid and also as circuit terminals and connections. Hence no separate circuit terminals or connections are 85 needed.

Tenth. The joints to be heated and cooled are hermetically sealed, and hence not subject to corrosion by the atmosphere.

We do not limit ourselves to the particular 90 materials constituting the thermo-electric elements herein specifically described, nor to the shell shaped in the form of a pyramidal frustum, nor to the configuration of the part A or its proportionate size as shown to the cell 95 proper, nor to the specific shape of the part D, nor to the relative proportionate masses of the substances within the cell.

We do not claim herein the construction and arrangement of the heating portion A, 100 either individually or in combination with the shell C, nor to the arrangement of heating-flues and connections resulting from the use of two or more such cells as here illustrated, nor the mode of electrically joining 105 said cells in battery or of connecting the tubes for the refrigerating fluid, these matters being fully described and claimed in another application for Letters Patent filed simultaneously herewith, Serial No. 21,904, 110 series of 1900.

We claim—

1. In a thermo-electric cell containing a mass forming one element of the thermo-electric couple, a tube in electrical connection with said mass and adapted to convey a current of refrigerating fluid through the body thereof, substantially as described. 115

2. In a thermo-electric cell containing a mass of metal forming one element of the thermo-electric couple, a joint to be cooled formed by embedding a tube within said mass, the said tube being adapted to convey a current of refrigerating fluid for cooling said joint by conduction through the wall of said tube, 120 substantially as described.

3. In a thermo-electric cell containing a joint to be heated, a joint to be cooled, and two tubes of conducting material electrically connected respectively with said joints but insulated from one another and adapted to convey a current of refrigerating liquid in proximity to said joint to be cooled, substantially 130 as described.

4. A thermo-electric cell having one element of the thermo-electric couple inclosed within the other element of said couple, a tube electrically connected with the inclosing element and insulated from the element inclosed and a tube electrically connected with the inclosed element and insulated from the inclosing element; the said tubes being insulated from one another and mechanically connected to convey fluid through said cell, substantially as described. 5
5. In a thermo-electric cell having a joint between the elements of the thermo-electric couple, whereat temperature differences produce differences in electrical potential, a shield interposed between said elements at said joint and constructed of electrically-conducting material incapable of attacking either of said elements, substantially as described. 15
6. In a thermo-electric cell, an electropositive element, an electronegative element capable of attacking the same, and a mass of electronegative metal incapable of attacking said electropositive element; the said mass being interposed between and in contact with said elements, substantially as described. 20
7. In a thermo-electric cell, an element of copper, a mass of conducting metal incapable of attacking said element, and an element of antimony-zinc alloy; the said mass being interposed between and in contact with said elements, substantially as described. 30
8. In a thermo-electric cell, an element of copper, a mass of antimony and an element of antimony-zinc alloy; the said antimony being interposed between and in contact with said elements, substantially as described. 35
9. The combination in a thermo-electric cell of an electropositive element, an electronegative element and a bent contact-piece having substantially-parallel arms, one of said arms being united to said positive element and the other to said negative element, substantially as described. 40
10. The combination in a thermo-electric cell of an electropositive element, an electronegative element and a bent contact-piece having substantially-parallel arms, one of said arms being united to said positive element and the other united to and embedded in said negative element, substantially as described. 45
11. The combination in a thermo-electric cell of the inclosing electropositive element A, C, Q internal electronegative element, insulated tube L electrically connected with said negative element and insulated tube N electrically connected with said positive element, substantially as described. 50
12. In a thermo-electric cell, having an outer electropositive shell and an inner electronegative solid mass, circulating-tubes for a refrigerating fluid embedded in metal within said shell, and a conducting-plate O between said metal and said electronegative mass, substantially as described. 55
13. A thermo-electric cell having a shell or envelop containing forty-two per cent. of copper, 0.08 per cent. of iron and fifty-seven per cent. of nickel, substantially as described. 60
